UNITED STATES PATENT OFFICE

2,031,760

HAIR CURLING DEVICE

Thomas N. Coffelder, Pittsburgh, Pa.

Application December 13, 1934, Serial No. 757,325

2 Claims. (Cl. 132—33)

This invention relates to hair curling apparatus for use in so-called permanent waving and it is among the objects of the invention to provide a device for curling the hair in an efficient and expedient manner and which shall be adapted to subject the hair to proper tension while it is being wound for curling.

One method of so-called permanent waving consists of segregating a tuft of hair and winding it around a spool-like member while simultaneously subjecting it to tension, then while retaining it on the spool subjecting it to heat for a suitable period of time so that when the spool is subsequently removed, the hair will retain its curled shape.

In accordance with the present invention, means are provided for the mechanical handling of the tufts of hair, particularly while it is wound preliminary to heat treatment to subject all of the strands to uniform tension without pull or strain on the scalp, and to this end a special frame is provided for supporting the spool in winding the strands while permitting it to slide on the frame with a regulable amount of friction to produce the desired tension.

The invention further consists in improvements for preventing burning or heating of the scalp and in an improved clamp for holding the strands of hair adjacent the scalp and further provides a support for the spool winding frame mounted to be universally movable relative to the head of the person on which the curling device is used.

These and other objects of the invention will become more apparent from a consideration of the accompanying drawings constituting a part hereof in which like reference characters designate like parts and in which:

Figure 1 is a plan view of a winding frame and spool together with a clamping mechanism in assembled position, the hair-winding device being illustrated as having the strands of hair partially wound thereon;

Figure 2 a side elevation of the curling spool; Figure 3 a bottom view in elevation of a hinged clamp;

Figure 4 an elevation of one of the clamping edges of the clamp shown in Figure 3;

Figure 5 a plan view of the clamp shown in Figures 3 and 4;

Figure 6 a sectional elevational view of the curling and steaming mechanism in assembled position;

Figure 7 a diagrammatic view illustrating the

support and curling frame together with a steam boiler;

Figure 8 a cross-section of a guard plate;

Figure 9 a plan view thereof; and

Figure 10 an end elevational view of the guard plate.

Referring to Figure 1, numeral 1 represents the scalp from which strands of hair 2 have been separated and clamped at 3. An insulating block 4 is disposed between the clamp and the head to prevent burning of excessive heating of the scalp. Clamp 3 is constructed as shown in Figures 3 to 5 inclusive and consists of a pair of hinged members having heavy rubber sections 5 constituting the clamping faces which come together at 6, Figure 5. The strands of hair are disposed between the rubber clamping edges as shown at 7, Figure 3, and a latch 8 locks the hinge members in place in the manner shown in Figure 3. Mounted on the top face of the clamp 10 blocks is a bracket 9 having extensions 11 for receiving grooves 12, Figures 1 and 2, of a spool 13, the latter being provided with a ratchet wheel 14 which engages a ratchet pawl 15 of the clamp, Figure 5, to prevent its rotation when inserted in the bracket 9. The spool is provided with a spring clamp bar 16 which is hinged at 17 so that it may be raised as shown by dotted lines in Figure 2. The ends of the hair strands are placed between the clamp bar 16 and the face of the spool 13, the clamp having gripping engagement by spring arms 18 with the body of the spool to securely hold it in place.

The spool is mounted on a slide bracket 19 movable on a frame 20 made of a cylindrical rod, 35 one end of the frame having a yoke 21 for receiving the clamp 3 which is snapped between the abutments 22. The yoke 21 is secured to the rods by pins 23 or in any other suitable manner. The slide bracket 19 is slidably mounted on the 40 frame 20 and provided with tension means 24 for varying the amount of frictional contact of the slide bracket with the frame to thereby vary the tension on the hair strands 2 as they are being wound on the spool 13.

The slide bracket 19 is provided with journals 25 and 26 for receiving pins 27 and 28 respectively, the pins fitting in the openings shown in dotted lines in the ends of the spool 13, Figure 2 of the drawings. A ratchet pawl 29 is mounted on slide 50 bracket 19 in alignment with ratchet wheel 14 of the spool to permit turning the spool in the direction of winding the hair strands thereon. By turning the knurled head 29 of the spool shaft, the spool will wind the hair strands and simul- 55

taneously cause the slide bracket 19 to move downwardly on the frame members 20 in the direction of clamp 3. The spool is then transferred to the bracket 9 of the clamp 3 and prevented from unwinding by the ratchet pawl 15. The frame 20 is disengaged and the wound hair strands are then ready for steam treatment. The frame member 20 is provided with hinged ear 30 for engaging a link 31 that is mounted on swivel arm 32, Figure 7, which in turn is hinged on a post or standard 33 that is transportable to the chair on which the person to be operated upon is reclining.

When the wound spool is attached to the bracket 9 of the clamp, the frame 20 is removed from the clamp 3 and a steam box 34 is snapped on the clamp as shown in Figure 6, the edge of the box fitting against the rubber face of the clamp 3 to provide a sealed joint. The box is provided with a conduit 35 communicating with the interior of the steam box at 36 and a vent hole 37 is provided at the other end of the box. A hose 38 is attached to the conduit 35, the hose leading to a manifold 39, Figure 7. Steam is generated in a boiler 40 having a fire-box 41 with tubes 42 leading to the exterior thereof, water being supplied overtop of the tubes and steam dome in the same casing, and the steam generated passes through a pipe line 43 to the manifold 39. The top of the boiler or manifold is open to prevent development of excessive steam pressure. A plurality of flexible hose connections 38, with springs wound on the inside or outside to carry the weight of the steam pocket, lead from the manifold 39 to a large number of steam boxes of the kind shown in Figure 6, each housing a wound strand or tuft of hair so that when all of the hair is wound, the steam treatment may be applied simultaneously to all of them.

To prevent excessive heating or burning of the scalp, a protector plate 4, Figures 8 to 10 inclusive, is placed adjacent the scalp in the manner shown in Figure 1. Plate 4 is of concave shape at 44 and is preferably a wooden block 45 lined with felt at 46 and 47. The block is in two parts hinged at 48 similar to the clamp 3, and is provided with a latch 49 to hold it together. This block clamp functions to clamp the hair and aids in preventing pull on the scalp in the same manner as the clamp block 3.

Referring to Figure 1, the spool 13 is interchangeable with slide bracket 19 and bracket 9 of the clamp 3 and is transferred from slide bracket 19 by withdrawing pins 27 and 28 after which it is placed in the bracket 9 and locked by

ratchet wheel 14 engaging the pawl 15 of the clamp. The same frame and slide bracket is then transferred by movement of the swinging arm and link 32 and 31 to another portion of the head for winding another tuft of hair. By thus supporting the frame 20 and by maintaining suitable adjustment of screws 24, a uniform tension is applied to the hair while being wound, thus assuring uniform results of the waving after the steam application to the wound hair. After the steam treatment, the steam boxes 34 are removed from the clamps. The clamps are separated by unlatching the members 8 and the rolls 13 are unwound and clamp 16 lifted to free the hair which is then brushed out in the usual manner.

It is apparent from the foregoing description of this invention that the winding and curling device is compact and of simple construction and does not require any separate tension means as heretofore proposed, and by the use of the universal support the hair may be wound preliminary to steaming in a minimum time with uniform results.

Although one embodiment of the invention has been herein illustrated and described, it will be apparent to those skilled in the art that various modifications may be made in the details of construction without departing from the principles herein set forth.

I claim:

1. A hair curling device comprising a clamp, a bifurcated frame having its ends in engagement with said clamp, a slide bracket in frictional engagement with said frame, and a spool interchangeably mounted on said guide bracket and clamp, means on said spool for clamping strands of hair, and means for rotating said spool whereby the slide bracket is moved on the frame against the resistance of its frictional engagement therewith and in the direction of the clamp.

2. A hair curling device comprising a clamp, a bifurcated frame having its ends in engagement with said clamp, a slide bracket in frictional engagement with said frame, and a spool interchangeably mounted on said guide bracket and clamp, means on said spool for clamping strands of hair, and means for rotating said spool whereby the slide bracket is moved on the frame against the resistance of its frictional engagement therewith and in the direction of the clamp, said spool being provided with a ratchet wheel and said guide bracket and clamp being provided with ratchet pawls for engagement with the wheel of the spool.

THOMAS N. COFFELDER.
